(57) **CLAIM**

The ornamental design for a portable cyclonic vacuum cleaner, as shown and described.

DESCRIPTION

FIG. 1 is a perspective view of a portable cyclonic vacuum cleaner showing our new design;

FIG. 2 is a left side elevation view thereof;

FIG. 3 is a front elevation view thereof;

FIG. 4 is a right side elevation view thereof;

FIG. 5 is a rear elevation view thereof; and,

FIG. 6 is a top plan view thereof.

The details shown in broken lines form no part of the design. The bottom of the portable cyclonic vacuum cleaner is plain and unadorned, and does not form part of the design.
